Primary Examiner — Eric Goodman*Assistant Examiner* — Sanjeev Paul(74) *Attorney, Agent, or Firm* — Vista IP Law Group, LLP(57) **CLAIM**

The ornamental design for virtual reality glasses, as shown and described.

DESCRIPTION

FIG. 1 is a front perspective view of virtual reality glasses;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines shown in the figures show portions of the virtual reality glasses that form no part of the claimed design.

1 Claim, 8 Drawing Sheets(56)
